US00D620016S

(12) **United States Design Patent**
Lo

(10) **Patent No.:** **US D620,016 S**
(45) **Date of Patent:** **** Jul. 20, 2010**

(54) **USB FLASH DISK**

(76) Inventor: **Yu-Nan Lo**, No. 8, Lane 45, Ciancun E. Rd., Daya Township, Taichung County 42852 (TW)

(**) Term: **14 Years**

(21) Appl. No.: **29/346,012**

(22) Filed: **Oct. 25, 2009**

(51) **LOC (9) Cl.** **14-02**

(52) **U.S. Cl.** **D14/480.6**

(58) **Field of Classification Search** D14/356,
D14/411, 433, 435.1, 436, 137, 155, 167,
